EZEKIEL J. MILES, OF DETROIT, MICHIGAN, ASSIGNOR TO STUDEBAKER CORPORATION, A CORPORATION OF NEW JERSEY.

MANIFOLD FOR INTERNAL-COMBUSTION ENGINES.

Application filed October 14, 1921. Serial No. 507,787.

To all whom it may concern:

Be it known that I, EZEKIEL J. MILES, a citizen of the United States of America, and resident of Detroit, in the county of Wayne 5 and State of Michigan, have invented certain new and useful Improvements in Manifolds for Internal-Combustion Engines, of which the following is a specification.

This invention relates to intake and exhaust passages for internal combustion engines, and has for its object to provide such passages as will promote easy starting of the engine, and will cause complete vaporization of the fuel without undue heating 15 of the fuel mixture, thus resulting in increased economy in fuel consumption, elimination of crank case dilution and prevention of spark plug fouling.

The method I use to attain these results 20 is to heat part of the intake passage by means of a substantial proportion of the exhaust gases. I am aware that there are many intake manifolds now in use employing a means to heat the same but which do 25 not attain the results desired as thoroughly as I attain them. Heretofore it has been customary to either by-pass a small portion of the exhaust gases from the exhaust manifold to a pocket on the intake manifold from 30 which it was then allowed to escape, or to provide a common wall between a portion of the intake and exhaust manifolds. When the exhaust gases are by-passed as described the action is not positive because of the two 35 paths which may be followed, and when there is a common wall as described the heating effect is only on a portion of the circumferential surface of the intake passage. Both of these features are undesirable 40 as has been shown by experiments I have personally conducted. These experiments carried on with an intake manifold having a glass face, show that the heavy fuel ends common to the present day fuel will not 45 vaporize without the direct application of considerable heat. Moreover, these heavy particles of fuel if not sufficiently heated come in contact with the walls of the intake passage and adhere thereto, collecting and 50 forming a stream of raw fuel which finally enters the cylinders in a liquid state. Some of this raw fuel works past the pistons into

the crankcase and dilutes the lubricating oil therein, while that part which is only partly burned forms a sooty deposit in the combustion chamber and on the spark plugs. If these heavy unvaporized particles of fuel can be brought into contact with a highly heated surface long enough to vaporize them without unnecessarily heating the entire 60 combustible mixture, the most advantageous conditions will be obtained as shown in the description of my present invention. I have observed in the experiments referred to above that the greater part of the heavy fuel 65 particles cling to the inside of the bend where the intake manifold branches from the carburetor to the various cylinders. This point, then, I consider to be the most important point for applying heat and accordingly I have designed my manifold so that this point and enough of the surrounding 70 surface is heated sufficiently to vaporize the heavy particles of fuel without unnecessarily heating the entire combustible mixture. In 75 order to insure the proper amount of heat at this point I have so designed the exhaust and intake manifolds that approximately half of the entire exhaust from the engine can be directed at and around it. This is 80 the preferable condition existing under normal running conditions altho I have provided a shutter which is capable of allowing the full proportion or none of the exhaust gases to be so directed. The construction is 85 such that immediately upon starting the exhaust gases are directed against and around a part of the intake manifold, insuring quick starting in the coldest weather.

To effect a more perfect understanding of 90 my present invention I will refer to the accompanying drawings in which—

Figure 1 is a partially broken side view of the exhaust and intake manifolds in assembled position.

Figure 2 is an end view of the exhaust and intake manifolds in assembled relation.

Figure 3 is a top view of the lower intake manifold.

Figure 4 is a sectional view of the exhaust manifold taken on the line XX of Figure 2.

Figure 5 is a sectional view of the exhaust manifold and upper intake manifold taken on the line AA of Figure 1, showing the

shutter in position so that all the exhaust gases from half of the engine cylinders must pass around the intake manifold, and

5 Figure 6 is a view corresponding to Figure 5 but showing the shutter in a position in which none of the exhaust gases come in contact with the intake manifold.

Referring to the numbered parts of the drawing, 1 is an exhaust manifold having 10 openings 2 thru which the exhaust gases from the engine cylinders enter the manifold and escape at 3. Between the two center openings 2 are provided the baffle walls 4, 5, and 6. The baffle wall 4 is positioned so that the exhaust gases from half of the cylinders must pass beneath it, the baffle wall 6 makes it necessary for the same gas to pass over it, and the baffle wall 5 makes it necessary for the gas to pass around 15 it as clearly shown in Figures 4 and 6 by the arrows 13. An opening is provided in the outer face of the manifold 1 adjacent these baffle walls. An upper intake manifold 7 provided with a vertical passage 20 terminating in a flange 8 for connection to a carburetor, branches into two passages at right angles to the vertical passage connected with the lower intake manifold 9 which directs the combustible mixture to the various cylinders. Around the branch of the upper intake manifold is a casing 10 providing a space between its inner wall and the outer wall of the intake manifold 7 and provided with an opening to match the opening 25 adjacent the baffle walls of the exhaust manifold 1. This casing envelopes part of the vertical passage and part of the passages which branch from this vertical passage. A pivoted shutter 11 operable by the lever 12 30 is provided longitudinal of the exhaust manifold 1 between the upper manifold passage 7 and the horizontal baffle wall 5. When this shutter is in the position shown in Figure 5 it has the effect of continuing the baffle wall 5 to the intake manifold 7, and the exhaust gases from half of the cylinders must pass under the baffle wall 4 around 35 and over the intake passage 7, over the baffle wall 6 and out thru 3. This results in a direct, positive, and highly heated gas stream passing around and heating the branching intake passage 7, for such a distance as to vaporize the heavy particles of fuel touching or adhering to walls of the 40 intake passage without unnecessarily heating the entire combustible mixture. The shutter or valve 11 may be turned to the position shown in Figure 6 which does not allow any of the exhaust gases to come in 45 contact with the intake manifold, or it may be moved to any intermediate position allowing a variation of the heating effect.

Formal changes may be made in the specific embodiment of the invention described without departing from the spirit or

substance of the broad invention, the scope of which is commensurate with the appended claims.

What I claim is:

1. In an internal combustion engine, an exhaust manifold, an intake manifold, a plurality of fixed baffles within said exhaust manifold and a movable baffle co-operating with all said baffles both for directing the exhaust gases toward and for directing the 75 exhaust gases away from said intake manifold.

2. In an internal combustion engine, an intake manifold, an exhaust manifold surrounding a portion of said intake manifold, 80 a fixed baffle extending longitudinally of said exhaust manifold, and a movable member to close the space between said baffle and said intake manifold and direct the exhaust gases around said intake manifold. 85

3. The combination with a multiple cylindered internal combustion engine of an exhaust manifold and an intake manifold, said exhaust manifold having approximately midway its length a downwardly depending baffle wall cutting off approximately the upper half of the exhaust passage, a horizontal baffle wall extending from the bottom of said downwardly extending baffle wall to the top of an upwardly extending baffle wall 90 which cuts off approximately the lower half of the exhaust passage, an opening in the face of said exhaust manifold between the first and last named baffle walls and of approximate equal dimensions on either side 95 of said horizontal baffle wall; said intake manifold provided with a branching passage, a shell surrounding the intake passages at the point of branching, provided with an opening therein adapted to register with the aforementioned opening in said exhaust passage, and a movable baffle extending from the intake passage within said shell to the horizontal baffle wall in said exhaust manifold, capable of causing the exhaust gases 100 from one half of the number of cylinders to pass around said branching intake passage within said shell. 105

4. In an internal combustion engine having a plurality of cylinders, an exhaust 115 manifold, a protruding portion thereon, an intake manifold having a branched passage, the branches of said intake manifold being inclosed in said protruding portion of said exhaust manifold, and means comprising a fixed baffle and a movable baffle for causing the exhaust gases from a portion of the engine cylinders to pass around said branched passages of said intake manifold. 120

5. In an internal combustion engine having a plurality of cylinders, an intake manifold for supplying combustible mixture to said cylinders, an exhaust manifold for conveying away the exhaust gases from said cylinders, said exhaust manifold inclosing a 125 130

- portion of said intake manifold, fixed baffles and a movable baffle within said exhaust manifold, said movable baffle being operable to co-operate with said fixed baffles to direct the exhaust gases from a part of said cylinders around that portion of said intake manifold within said exhaust manifold.
6. In an internal combustion engine, a plurality of cylinders, a branched intake manifold for supplying combustible mixture to said cylinders, an exhaust manifold for conveying away the exhaust gases from said cylinders, the portion of said intake manifold adjacent the point of branching being inclosed by the walls of said exhaust manifold, and fixed baffles within said exhaust manifold co-operating with a swinging baffle adjacent said intake manifold for directing the exhaust gases from a part of said cylinders around the branched portion of said intake manifold in one direction only.
7. In an internal combustion engine having a plurality of cylinders, an exhaust manifold and an intake manifold, said intake manifold including a vertical passage branching into two substantially horizontal passages, the portion of said intake manifold adjacent the point of branching being inclosed by a projection on said exhaust manifold; a downwardly depending baffle and an upwardly projecting baffle in said exhaust manifold adjacent the end of the branched portion of said intake manifold within said exhaust manifold, a horizontal baffle wall connecting said downwardly depending and upwardly projecting baffle walls, and means for extending said horizontal baffle wall from said branched portion of said intake manifold to the adjacent wall of said exhaust manifold.

Signed by me at Detroit, Michigan, this 11th day of October, 1921.

EZEKIEL J. MILES.
